APPARATUS FOR INTRODUCING AIR TO INSULATED ELECTRODE STRUCTURES IN ELECTRICAL PRECIPITATORS

Floyd H. Viets, Glendale, Calif., assignor to Western Precipitation Corporation, Los Angeles, Calif., a corporation of California

Application October 25, 1947, Serial No. 782,076

11 Claims. (Cl. 183—7)

1

The present invention relates generally to electrical precipitators for removing suspended particles from a stream of gas, and more particularly to means for introducing compressed air or other gaseous fluid into the housing of an electrical precipitator in such a way that there is no need for a rubber hose or similar insulating section in the compressed air supply means to prevent grounding the high tension electrode.

In electrical precipitators, the stream of gas carrying particles in suspension passes through one or more electric fields in which the suspended particles receive a charge and are then moved, under the influence of an electric field, toward a collecting electrode. When the collected material is a dry solid, it ordinarily accumulates upon the surface of the collecting electrode, and it becomes necessary to clean the electrode periodically in order to maintain the efficiency of the precipitator. Under these circumstances, cleaning an electrode can be accomplished by delivering a series of sharp blows to the electrode to jar or shake loose the accumulated material which, of its own weight, then falls downwardly to some point beneath the electrode.

The bulk of the suspended material ordinarily accumulates upon the grounded collecting electrode, and there is no problem of grounding the electrode involved in cleaning it. The hammer or other means for jarring the collecting electrode is commonly operated by compressed air; and since the collecting electrode is grounded to the precipitator shell, a metallic conduit for compressed air may be used leading to the hammer means.

It is quite common for a considerable portion of the material suspended in the gas stream to be deposited upon the high tension electrode, and it is in cleaning this electrode that the problem particularly arises of operating a suitable hammer or shaking mechanism without grounding the high tension electrode. Various types of automatic operating mechanisms for electrode rappers have been devised, and certain of them require compressed air. In the case of a rapping mechanism of this type, when applied to a high tension electrode, there is a problem of conducting the compressed air through the precipitator shell to the rapper while at the same time maintaining the high tension electrode insulated from ground and from the other low tension portions of the precipitator shell.

Because my invention has been designed and adapted to the solution of this problem in connection with the operation of rappers for high ten-

2

sion electrodes, I show my invention in this particular embodiment. However, it will be understood that my invention is not necessarily limited to this application, but may be used in connection with any other type of mechanism operated or actuated by air pressure which must be kept insulated electrically.

Thus it becomes a general object of my invention to provide means for leading a fluid supply line to a fluid-pressure actuated rapper mounted upon a high tension electrode without grounding the electrode and without connecting that electrode electrically to the shell or other similar portion of the precipitator.

It is also an object of my invention to provide means for conducting a supply of compressed air or the like to a fluid-pressure actuated rapper or similar device in an electrical precipitator, without relying upon conduit sections made from rubber or other insulating materials which are subject to deterioration under high temperatures and upon exposure to acid or other chemical fumes.

The above and other objects of my invention are attained by providing, in connection with a fluid-pressure actuated rapping or similar device on a high tension electrode, fluid supply means for the rapper which comprises a lead-in which includes an insulator member or section engaging a grounded member or part of the shell. In one form of my invention the lead-in may comprise a suspension member for supporting and electrically insulating the electrode assembly from the shell. The lead-in has a fluid passage extending through it and communicating at one end with the interior of a grounded housing which encloses that end of the lead-in or suspension member. The grounded housing is connected to means for supplying gaseous fluid under pressure to the housing interior, the fluid then flowing through the passage within the lead-in to a conduit at the other end which is connected with the rapping device.

How the above objects and advantages of my invention, as well as others not specifically mentioned herein, are attained will be more readily apparent by reference to the following description and to the annexed drawings, in which:

Fig. 1 is a fragmentary vertical section through a typical electrical precipitator looking in the direction of gas flow, showing the high tension and collecting electrode assemblies with a rapping device attached to the high tension assembly, and means for supplying fluid under pressure to the rapper;

Fig. 2 is a fragmentary vertical section through the upper end of the high tension electrode assembly on line 2—2 of Fig. 1, showing the rapping device in side elevation;

Fig. 3 is an enlarged vertical section on line 3—3 of Fig. 1 through the top end of an insulator for the high tension electrode assembly showing the filter mounted at the upper end of the insulator;

Fig. 4 is an enlarged fragmentary elevation and section taken on line 4—4 of Fig. 1 showing the lower end of the electrode assembly suspension member, the fluid passage therein, and the connection with the conduit leading to the rapping device; and

Fig. 5 is a fragmentary vertical section through an electrical precipitator showing a modified form of my invention.

In order to illustrate and disclose my invention, Fig. 1 shows a portion of an electrical precipitator which is typical of industrial precipitators for collecting dry solids suspended in a stream of gas. Because the details of construction and arrangement of the various parts of an electrical precipitator are, in general, well known to persons skilled in the art and are not a part of the present invention, description of such details will be limited here to a disclosure of those necessary to understand how my invention may be applied or adapted to a typical precipitator construction. It will be understood that my invention is in no way limited to the particular precipitator construction shown herein, nor to any one particular type of fluid-pressure actuated rapping means for the electrodes; but the invention may be applied equally well to other precipitators and to various types of rappers. Modifications in the locations and connections between the several parts are within the scope of persons skilled in the art.

The electrical precipitator in Fig. 1 is contained within a housing or shell 10 which not only encloses the electrode assembly but also provides a duct through which the dust-laden gas stream flows. The direction of gas flow is perpendicular to the plane of the drawing. The structural framework of the precipitator includes posts 14 within shell 10 which support at their upper ends transverse beam 15 at the top of the gas duct. From two such beams 15, spaced in the direction of gas flow, are suspended a plurality of plates 16 which extend parallel to the direction of gas flow. Plates 16 constitute individual collecting electrodes. The collecting electrode assembly, including plates 16 and beams 15, are all connected together, both electrically and mechanically, and are connected to shell 10. Since shell 10 is grounded electrically, all these parts are also grounded through the shell.

The high tension electrode assembly comprises a pair of transverse members, of which only the upper channel member 18 is shown. The lower member is similar to the one illustrated and is positioned directly beneath it. The upper and lower transverse members 18 are connected by a pair of vertically extending members 19, here shown as angles, thus forming a generally rectangular end frame. Two such end frames, spaced apart in the direction of gas flow, support between them a plurality of pipes 20, or other similar longitudinally extending members. As may be seen best in Fig. 2, pipes 20 are attached to transverse beams 18 by U-bolts 21, or other similar means. Pipes 20 extend in the direction of gas flow, and are parallel to and midway between two collecting electrodes 16. Suspended

from each pipe 20 is a plurality of rod or wire elements 22 which are the discharge electrodes.

Each of the rectangular end frames of the high tension electrode assembly just described, is suspended by two hanger rods or tubes 24 which are attached at their lower ends to upright members 19 and extend upwardly through sleeves 25 into insulators 26. At least certain ones of hangers 24 are hollow in order to provide for a fluid supply passage, as will be explained in greater detail. Otherwise, the members 24 may be solid rods. Each hanger 24 is secured at its upper end to a metal cap 28 which rests upon the top of an insulator 26, as shown in detail in Fig. 3. Each insulator 26 has an enlarged portion which rests upon a flange provided by housing 27, in order to support the insulator. The joint between insulator 26 and the flange of housing 27 is made fluid-tight, and for this purpose a gasket or other means between the insulator and housing flange may be employed. This fluid-tight connection not only keeps the gases being treated from escaping upwardly through housing 27, as in the case of the right-hand insulator in Fig. 1, but also prevents compressed air from entering the gas duct, as in the case of the left-hand insulator in Fig. 1.

The device for rapping the electrode assembly is indicated generally at 30, and is rigidly attached to the under side of a top transverse member 18 by its upper flange 31. It has been found by experience that this is a particularly effective point at which to deliver the rapping blows. However, the rapping device may be attached to any other member of the electrode assembly, and more than one rapper for each assembly may be used, if desired. The rapping device comprises two housing portions 32 and 33 which are bolted together and provide a cylinder within which a piston, indicated at 37 in Fig. 2, is movable under air pressure. Exhaust ports (not shown) in the cylinder are covered by a shield 34 to prevent entry of foreign matter into the cylinder. The details of the internal construction of the rapping device 30 are not shown in this application. Reference may be had to my co-pending application Ser. No. 715,020, filed December 9, 1946, on "Pneumatic Method and Apparatus for Rapping Electrodes in Electrical Precipitators," for detailed information regarding the construction and operation of this particular type of rapping device.

Gaseous fluid under pressure is supplied to rapping device 30 by fluid supply means which includes a length of flexible metal hose 35 attached to a fitting on lower body portion 33 by an elbow 36, and also pipe 38 which is connected to the other end of hose 35. Pipe 38 is held in place by brackets 39 bolted to angle 40 which is attached to one face of channel 18. Pipe 38 is connected to pipe 41 by elbows 42 and 43 and an intervening nipple. Pipe 41 is located within, and extends vertically for the full length of one of the hollow suspension members 24 for the electrode assembly.

Pipe 41 is fastened at its upper end to plug 45 which is welded or otherwise secured in place within the upper end of suspension member 24. Plug 45 effects a fluid-tight closure of the interior of member 24 to prevent the passage of fluids into or out of the precipitator shell through this hollow member. Cap member 48 is screwed onto the upper end of pipe 41, as shown in Fig. 3, and is provided with a pair of small passages 50 which provide communication between the interior of pipe 41 and the exterior of cap 48.

In the operation of the particular rapping de-

vice indicated at 30 and described in detail in my co-pending application referred to above, it is desirable that there be one or more small orifices in the fluid supply means in order to effect a degree of control over the flow of air through the supply means. For this purpose orifices 50 are provided; but it will be understood that it is within the scope of my invention to eliminate cap 48 and orifices 50 entirely, as the fluid supply means might just as well be used to supply fluid to some other type of mechanism in which the flow control afforded by these orifices is unnecessary. It is desirable to surround orifices 50 with a suitable filter, such as wire cloth screen 51, in order to remove from the fluid any solid particles which might lodge in passages 50 and interfere with the flow therethrough of fluid.

The fluid supply means also includes air line 52 and bell housing 53 which covers or encloses the upper end of insulator 23 and is secured to the top of housing 27 in such a manner as to effect a fluid-tight joint therewith. Bell housing 53 being connected electrically to housing 27, the former is electrically grounded by this connection to shell 10. Pipe 41, cap 48, and filter 51 are connected electrically to the high tension electrode assembly through hanger rod 24, and are consequently maintained at relatively high potential. For this reason, housing 53 must be everywhere sufficiently spaced from filter 51 that no spark-over can occur between the housing and filter 51 or any other nearby high tension parts.

Air line 52 is connected to any suitable source of compressed air, or other gaseous fluid under pressure which is adapted to use by some mechanism within the precipitator, such as tank 54 in which air is stored by a compressor unit, not shown. It may be desirable, although not necessary, to attach several lines 52 to a single tank 54 by means of a distribution valve or manifold D.

Fluid under pressure is conducted from tank 54, or other suitable source, by line 52 into bell housing 53 which forms a part of the means supplying fluid under pressure. Housing 53 encloses and defines a spaced filled by fluid under pressure and surrounding the upper ends of insulator 26 and fluid supply pipe 41. The walls of the housing are sufficiently spaced from these parts that there is no danger of grounding or short-circuiting the high tension elements through this fluid body. The interior of pipe 41 communicates with the space inside housing 53, in this particular instance through orifices 50 and cap 48, and air under pressure flows from the interior of the housing down through pipe 41, pipe 38, and hose 53, to rapping device 30.

It is within the scope of my invention to eliminate pipe 41 as a separate member, and use the wall of tube 24 to define the fluid supply passage. In this way, the electrode assembly suspension member and fluid passage means are combined into a single element. However, it is preferable to utilize the construction shown in the drawings since the weight of the electrode assembly is ordinarily so great that a pipe of small diameter, such as tube 41, is not sufficiently strong to carry the imposed load; and on the other hand a large diameter member such as tube 24 may supply the compressed air at a greater rate than is desired.

In the form of my invention just described, the lead-in for the fluid supply is an assembly comprising insulators 26 and 28 and pipes 24 and 41, plus various minor parts. As an example of how this lead-in assembly can be simplified, reference may be had to Fig. 5 in which is shown a varia-

tional form of my invention which differs from the foregoing chiefly in two respects. In the first place, the lead-in of Fig. 5 performs no supporting function, since it carries no weight except its own; and in the second place the rapper is not mounted directly on the electrode, but it is maintained at a high potential since it is connected electrically to the high tension electrode.

In this form of the invention, a housing 51 is mounted upon precipitator shell 10 and has within it a fluid-pressure operated vibrator or rapper 60. Rapper 60 is mounted on the upper end of rod 61 which passes downwardly through sleeve 62 supported upon disc-type insulator 63. The lower end of rod 61 is constrained to vertical movement by guide 64 which is mounted by channel 65 on the top of transverse electrode member 18. Without going into the details of operation, it is sufficient to say that vibrator 60, upon receiving compressed air, causes rod 61 to move up and down rapidly, striking a series of sharp blows against plate 66 on channel 65. The vibration travels through channels 65 to channel 18, thus jarring the electrode assembly so that the accumulated deposits fall off. Channels 65 may be attached to more than one transverse channel 18.

At the upper end of housing 57 is a hollow elongated insulator 68 mounted near its midpoint on plate 69 in such a fashion that the insulator and plate make a fluid-tight joint with the top wall of housing 57. Also on top of housing 57, is mounted bell housing 70, the joint between the two housings being fluid-tight so that the interior of housing 70 is adapted to hold fluid under pressure. A part of the top wall of housing 57 is common to housing 70 and may be considered a part of the latter in order to make of housing 70 a complete enclosure able to contain compressed air inside. Fluid is supplied under pressure to the interior of housing 70 through line 52.

The upper end of insulator 68 extends into and communicates with the interior of housing 70 so that fluid under pressure may flow from the interior of the housing into and through fluid passage means in the form of pipe 71 which extends longitudinally for the full length of insulator 68. The lower end of pipe 71 is connected by a length of flexible metallic hose 72 to vibrator 60 to supply fluid under pressure to the vibrator.

In order to effect a fluid-tight seal between the insulator and tube 71, the tube is threaded into nuts 74 and 75 at the upper and lower ends respectively of the insulator. Suitable gaskets are provided underneath these nuts to obtain the necessary seal with the insulator. Housing 70 is of sufficiently large diameter that no spark-over can occur to nut 74 or other high tension part.

As in the form of my invention previously described, it will be appreciated that housing 57 and 70 are electrically grounded through their connection to shell 10. The lead-in for conducting the supply of fluid into the shell consists of insulator 68 and tube 71, the latter being at high potential because of its electrical connection to the high tension electrode assembly and its insulation from the low tension or grounded portions of the precipitator by means of insulator 68. Insulator 68 carries little or no load, except its own weight; and performs no suspension function relative to the electrodes. It is preferred that the fluid passage through the insulator be formed by pipe 71 in order that fluid-tight connections can easily be made; but it will be understood that it is within the scope of my invention to have the fluid

passage formed by the body of the insulator itself and omit pipe 71, except as a similar pipe is connected to one end of the insulator.

Having disclosed a preferred form of my invention, it will be apparent that various changes in construction and arrangement of parts may be made by persons skilled in the art without departing from the spirit and scope of my invention; and consequently I wish it understood that the foregoing description is considered as being illustrative of, rather than limitative upon, the appended claims.

I claim:

1. In an electrical precipitator, fluid supply means for introducing gaseous fluid under pressure into the precipitator shell, comprising: a grounded housing defining a space adapted to contain fluid under pressure; an insulator extending into said space and provided with fluid passage means for conducting fluid under pressure from said space; and a conduit at high potential connected to and receiving fluid from said passage means.

2. In an electrical precipitator, fluid supply means for introducing gaseous fluid under pressure into the precipitator shell, comprising: a housing maintained at low potential and enclosing a space adapted to contain fluid under pressure; electrically conductive fluid passage means electrically connected to an electrode at high potential, and communicating with the body of fluid in said housing to receive fluid under pressure therefrom; and insulator means engaging the housing and surrounding the fluid passage means where it enters the housing to electrically insulate the passage means from the housing.

3. In an electrical precipitator as in claim 2, the combination including a fluid-pressure actuated rapping operatively engaging the electrode at high potential and supplied with fluid under pressure by said fluid passage means.

4. In an electrical precipitator having a high tension electrode within a grounded shell and a fluid-pressure actuated device on the electrode, means for supplying gaseous fluid under pressure to the device, comprising: a vertically elongated high tension electrode suspension member in contact with a grounded member and having a longitudinally extending fluid passage therein; a fluid-tight grounded housing enclosing the upper end of the suspension member and defining an interior space containing fluid under pressure and communicating with said fluid passage; means for supplying fluid under pressure to the housing interior; and conduit means connecting the fluid passage to the device.

5. In an electrical precipitator having a high tension electrode within a grounded shell and a fluid-pressure actuated rapping device on the electrode, means for supplying gaseous fluid under pressure to the rapping device, comprising: a vertically elongated high tension electrode suspension member in contact with a grounded member and having a longitudinally extending fluid passage therein; a fluid-tight grounded housing enclosing the upper end of the suspension member and defining an interior space containing fluid under pressure and communicating with said fluid passage; means for supplying fluid under pressure to the housing interior; and conduit means connecting the fluid passage to the rapping device.

6. In an electrical precipitator having a high tension electrode assembly within a grounded shell, the combination comprising: a cylinder rigidly attached to a member of the electrode as-

sembly and containing a fluid-pressure actuated piston; and means for supplying gaseous fluid under pressure to the cylinder to actuate the piston, said means comprising a high tension electrode assembly suspension member including an insulator section engaging a grounded member to support and insulate the electrode assembly, said suspension member having a fluid passage therein, a grounded housing enclosing one end of the suspension member and communicating with the fluid passage therein, means for supplying fluid under pressure to the interior of said housing, and a conduit connecting the fluid passage with the cylinder.

15 7. In an electrical precipitator having a high tension electrode assembly within a grounded shell and a fluid-pressure actuated device for rapping the electrode assembly, means for supplying gaseous fluid under pressure to the device, comprising: a grounded fluid-tight housing enclosing a space adapted to receive and contain gaseous fluid under pressure; an insulator extending through one wall of the housing and provided with fluid passage means communicating with said space to receive gaseous fluid therefrom; and a conduit connected to said insulator and insulated thereby from said wall, communicating with said fluid passage means and connected to the fluid-pressure actuated device for conducting gaseous fluid to said device.

20 8. In an electrical precipitator having a high tension electrode assembly within a grounded shell and a fluid-pressure actuated device for rapping the assembly, means for supplying gaseous fluid under pressure to the device, comprising: a grounded fluid-tight housing having a wall separating the interior thereof from the shell interior; inlet means for supplying gaseous fluid under pressure to said space; an insulator connected to said wall and provided with fluid passage means communicating with said space to receive gaseous fluid therefrom; and a conduit connected to said insulator and communicating with said fluid passage means and extending into the shell for conducting fluid to said device.

25 9. In an electrical precipitator, the combination comprising: a grounded shell for enclosing a stream of dust-laden gas to be treated; a fluid-tight housing supported by the shell and electrically connected thereto, the housing being adapted to contain a gaseous fluid under pressure; fluid inlet means connected to a housing wall for introducing gaseous fluid under pressure into said housing; and a high tension insulator extending from inside the housing through a housing wall, and having fluid passage means therein for conducting fluid under pressure out of said housing.

30 10. In an electrical precipitator, the combination comprising: a grounded shell enclosing a stream of dust-laden gas to be treated; a fluid-tight housing having one wall separating the shell interior from the housing interior, the housing being adapted to contain gaseous fluid under pressure; means for supplying fluid under pressure to the housing; and an electrical insulator passing through said one wall and having internal passage means for conducting fluid under pressure out of the housing to the shell interior.

35 11. In an electrical precipitator, the combination comprising: a grounded shell enclosing a stream of dust-laden gas to be treated; a fluid-tight housing having one wall separating the shell interior from the housing interior, the housing being adapted to contain a gaseous fluid under pressure; means for supplying fluid under pressure

40 45 50 55 60 65 70 75

to the housing; an electrical insulator passing through said one wall; and an electrode suspension member bearing on top of the insulator and extending through the insulator, the suspension member having fluid passage means for conducting fluid under pressure out of the housing.
